UNITED STATES PATENT OFFICE

161,233

GAME APPARATUS

Joseph Berkowitz, Kansas City, Mo.

Application June 17, 1949, Serial No. 3,375

Term of patent 3½ years

(Cl. D34—5)

To all whom it may concern:

Be it known that I, Joseph Berkowitz, a citizen of the United States, residing at Kansas City, in the county of Jackson and State of Missouri, have invented a new, original, and ornamental Design for a Game Apparatus, of which the following is a specification, reference being had to the accompanying drawing, forming part thereof.

Fig. 1 is a top perspective view of the game apparatus, showing my new design;

Fig. 2 is a side elevational view thereof;

Fig. 3 is a top plan view thereof; and

Fig. 4 is a bottom perspective view thereof.

I claim:
The ornamental design for a game apparatus, as shown.

JOSEPH BERKOWITZ.
